UNITED STATES PATENT OFFICE.

JAMES LESLIE FAIRRIE, OF LIVERPOOL, ENGLAND.

APPARATUS FOR DRYING MATERIALS, ESPECIALLY LEATHER, BY MEANS OF GASES.

1,371,083.

Specification of Letters Patent.

Patented Mar. 8, 1921.

Application filed November 6, 1920. Serial No. 422,298.

To all whom it may concern:

Be it known that I, JAMES LESLIE FAIRRIE, subject of the King of Great Britain, residing in Liverpool, in the county of Lancaster and Kingdom of England, have invented 5 certain new and useful Improved Apparatus for Drying Materials, Especially Leather, by Means of Gases, of which the following is a specification.

10 This invention relates to an improved process and apparatus for drying materials especially organic materials having an organized structure *e. g.* leather, or wood by means of gases, especially by heated atmospheric air.

Drying leather is a particularly delicate operation, because while it is desired to effect drying in the minimum time, it is also necessary to prevent injury to the material 20 or deterioration of the material. In the first place there is a temperature which it is desirable not to exceed throughout the operations, and in the second place it appears to be undesirable to remove the moisture from 25 the surface layer more rapidly than moisture can be supplied from the under-lying layers probably by capillary action; if therefore the air which is used is too dry, the moisture is evaporated from the surface 30 too rapidly and this surface deteriorates by becoming hardened. These difficulties are experienced particularly in the case of heavy leather, and the present invention aims especially at overcoming these difficulties in this 35 case, but the invention is not limited thereto, since it may be applied to any type of drying in which it is desired to maintain constant conditions of humidity and preferably of temperature also.

40 To this end the invention consists in a drier having a hygrometer or equivalent, and means controlled thereby for adjusting the humidity of the gas entering the drier, preferably by varying the relative proportion 45 of atmospheric air and air leaving the drier and by-passed back to mingle with the atmospheric air entering the drier. The invention further consists in a drier provided with a wet-bulb thermometer and a 50 relay or equivalent controlled thereby and adapted to add moisture to the air entering the drier to maintain a constant humidity at constant (dry-bulb) temperature. The invention further consists in a drier main- 55 tained at constant (dry-bulb) temperature

and having a wet-bulb thermometer operating a relay which controls a valve to vary the relative proportions of atmospheric air and air leaving the drier to make a mixture of constant humidity to enter the drier. 60

The invention further consists in a drier having means for positively controlling the humidity of the entering air as above described in combination with a dry-bulb thermometer or equivalent, and means to regulate the temperature of the gas which means may consist of adjustable steam heaters, for instance a plurality of steam valves may be employed each of which may be adjustable roughly by hand and controlled by a thermostatic controlling device operated on the gust principle *i. e.* to cut off the steam absolutely or to leave it full on in accordance with the control of a relay actuated by the thermometer. 70

A preferred form of the apparatus is shown in the accompanying drawings in which:—

Figure 1 is an elevation,

Fig. 2 is a plan,

Fig. 3 is a cross section,

Fig. 4 is a detail of the slide valve.

Fig. 5 is a detail view showing the thermostatic means of controlling the air heater. 75

In these drawings *x* is a chamber to contain the hides, carried by a bogey *y*. This chamber may be in the form of a tunnel through which atmospheric air may be blown by means of a fan or blower *a*, having a fresh air inlet *d*. The path of the relatively dry air is shown by single arrows. Thus air is maintained at constant humidity as hereafter described. The path of the moist air leaving the hides or the like is shown by double arrows. Thus air passes 85 from the tunnel *x* to the conduit *e*. Part of this moist air is by-passed through the fan and the mixture of moist air from *e* and atmospheric air from *d* enters the tunnel from the conduit *f* after passing through 90 the thermostatic steam heater *c* which may be of any known type, *e. g.* the usual kind operated on the gust principle in which steam is allowed to flow into the heater in 95 gusts under control of the thermostatic device in accordance with the temperature variations of the air. In Fig. 5 is shown in detail the device for controlling this steam supply to the heater through the intervention of the dry bulb thermometer *m*. 100 105 110

In this figure 41 are the electric connections leading to the relay 42. 43 are the supply mains and 44 is the circuit operating the solenoid 45 which raises the valve 47 by the stem 46 forming a part thereof, thereby cutting off the steam-supply from steam-pipe 48 to the pipe 49 leading to the air-heater *c*. This solenoid comes into operation when the temperature rises above a given point, therefore 5 by cutting off the steam. As soon thereafter as the temperature again falls below the determined maximum, the circuit of the solenoid is broken, the valve drops, and steam is again admitted from pipe 48 to the heater 10 *c* through the pipe 49. Fig. 4 shows a detail of the slide valve *b* which is raised and lowered by the guide *k*. The guide *k* is in the form of a rod which passes through the interior of the solenoid *k'*, arranged in the 15 electric circuit *p*, which circuit is adapted to be opened or closed by the wet bulb thermometer *n*, as indicated in said Fig. 4, thereby energizing the solenoid and moving the rod to lower or raise the slide valve *b*, as 20 will be readily understood. Thereby, when the thermometer *n* falls, the moist air supply to the air current passing into the drier is cut off or diminished, and when it rises, it is restored or increased. Dry air enters at 25 30 *g*, and moist air enters at *j* either from the tunnel as above described or from any other source.

The air of constant humidity leaves at *h*. The moist air exhaust is at *l*. This slide 35 valve is not an essential feature of the arrangement as moisture can be added to the air in any suitable manner provided this is under the control of the hygrometer. Fig. 1 shows a dry-bulb thermometer *m* controlling the heater and a wet bulb thermometer *n* controlling the slide valve through any 40 suitable relay devices acting on *k*.

The steam heater valves may be adjusted roughly by hand. 45

It will be seen that in the above described apparatus it is possible to fix the temperature and humidity in a very satisfactory manner. The predetermined humidity must be at least equal to the maximum humidity 50 of the atmospheric air during the period within which the adjustment is not altered, unless of course drying means are provided for the gases prior to entering the drier. It may be interpolated here that the above 55 mentioned method of humidity control applies also to cases in which dry air is used, but as in such cases it is easier to obtain constant humidity, the invention finds its primary application in cases when ordinary

atmospheric air is employed as the gas enters the drier. 60

It will be understood of course that the adjustment of the relay devices operated by the dry-bulb and wet-bulb thermometers may be altered either week by week or day 65 by day or even oftener if desired in accordance with changing atmospheric conditions or otherwise.

Clearly when a wet-bulb thermometer is employed, it is also necessary to maintain 70 a constant dry-bulb temperature if a constant humidity is to be maintained by constancy of the wet-bulb temperature.

I declare that what I claim is:—

1. In a drier, means to maintain constant 75 (dry-bulb) temperature, a wet-bulb thermometer adapted to control a valve to vary the relative proportions of atmospheric air and moist air to make a mixture of constant humidity to enter the drier. 80

2. A drier having a hygrometer and means controlled thereby for adjusting the humidity of the gas entering the drier including means for by-passing part of the moist air leaving the drier to mingle with 85 the atmospheric air entering the drier.

3. In a drier, means for passing an air-current through the drying chamber, means for heating said air to a fixed temperature, and a duct for carrying off the moist air 90 from the said drying chamber, in combination with means for causing moist air from said duct to flow into said air-current, a wet bulb thermometer arranged in the air current and connections between the same and 95 the means for causing the moist air to flow into the air current, whereby the wet bulb thermometer alone controls the latter.

4. In a drier, means for passing an air current through a drying chamber and 100 means for maintaining the heat of said air current at a fixed temperature, in combination with a wet bulb thermometer arranged in contact with the air in the drying chamber, and means for introducing moist air 105 into the air current before entering the drying chamber and connections between the wet-bulb thermometer and the moist-air introducing means to control the latter from the wet bulb thermometer. 110

In witness whereof, I have hereunto signed my name this 25th day of October, 1920, in the presence of two subscribing witnesses.

JAMES LESLIE FAIRRIE.
